OCCUPANT-BODY-STEERABLE SELF-PROPEL-
LABLE AQUAPLANE OR SIMILAR ARTICLE

Joe E. Piazza, Pacifica, Calif., assignor to Leisure
Products Corporation, Menlo Park, Calif.

Filed Apr. 15, 1970, Ser. No. 22,450

Term of patent 14 years

Int. Cl. D21—03

U.S. Cl. D71—1

FIG-2

FIG-3

FIG-4

FIG. 5

FIG. 6

FIG. 1 is a perspective view of the occupant-body-steerable self-propellable aquaplane or similar article embodying the design hereof, looking at one side toward the rear;

FIG. 2 is a top plan view;

FIG. 3 is an elevational view of the starboard side, the opposite port side having the same appearance;

FIG. 4 is a rear elevational view;

FIG. 5 is a bottom plan view; and

FIG. 6 is a front elevational view.

I claim:

The ornamental design for an occupant-body-steerable self-propellable aquaplane or similar article, substantially as shown and described.
